UNITED STATES PATENT OFFICE.

PHILLIP EBELING, OF WASHINGTON, PENNSYLVANIA, ASSIGNOR TO IMPERIAL
GLASS COMPANY, OF BELLAIRE, OHIO, A CORPORATION OF OHIO.

DESIGN FOR AN ARTICLE OF GLASSWARE.

55,759.

Specification for Design.

Patented July 13, 1920.

Application filed May 19, 1920. Serial No. 382,604. Term of patent 14 years.

To all whom it may concern:

Be it known that I, PHILLIP EBELING, a citizen of the United States of America, and resident of Washington, county of Washington and State of Pennsylvania, have invented a new, original, and ornamental Design for an Article of Glassware, of which the following is a specification, reference being had to the accompanying drawings, in which—

Figure 1 is a side elevation of an article of glassware, showing my new design, and

Fig. 2 is a partial sectional view of the same.

I claim:

The ornamental design for an article of glassware, as shown.

In testimony whereof, I affix my signature in the presence of two witnesses.

PHILLIP EBELING.

Witnesses:

J. RALPH BOYD,
SAMUEL A. MARTIN.
